(57) **CLAIM**

The ornamental design for an automobile window plasma tint, as shown and described.

DESCRIPTION

FIG. 1 is a front perspective view of an automobile window plasma tint showing my new design;

FIG. 2 is a front view; opposite back view is a mirror-image thereof;

FIG. 3 is a side view thereof;

FIG. 4 is an opposite side view thereof;

FIG. 5 is a top view thereof; and,

FIG. 6 is a bottom view thereof.

In FIG. 2, the broken lines showing the environmental structure for purposes of illustrating the automobile window plasma tint in a condition of use. The broken lines and the structure they depict form no part of the claimed design.
